UNITED STATES PATENT OFFICE.

HAROLD H. DOSWELL AND ARTHUR E. KOVER, OF FORT WAYNE, INDIANA.

FORM FOR PLASTIC BURIAL VAULTS.

1,409,686.

Specification of Letters Patent. Patented Mar. 14, 1922.

Application filed March 24, 1921. Serial No. 455,358.

To all whom it may concern:

Be it known that we, HAROLD H. DOSWELL and ARTHUR E. KOVER, citizens of the United States, residing at Fort Wayne, in the 5 county of Allen and State of Indiana, have invented new and useful Improvements in Forms for Plastic Burial Vaults, of which the following is a specification.

The invention relates to forms for the manufacture of burial vaults out of plastic material, and of the type commonly known as automatic sealing and water expelling cement burial vaults comprising a base and cover, the base extending into the cover and 15 supporting the casket within the cover and the cover seating on a flange at the bottom of the base.

The object of the invention is to provide a novel form or mold which shall be collapsible and adjustable and by which burial vaults may be manufactured rapidly and accurately, danger of injury to the vault by cracking or tearing when removed from the form being eliminated.

25 The invention consists in an inner form member for the cover composed of four overlapping and adjustable parts adapted to be rigidly secured together and a knock-down outer form member, an embodiment of the 30 same being illustrated in the drawings, in which drawings—

Figure 1 is a side elevational view of the assembled exterior form for the cover or bell of the vault; Fig. 2 an end elevational view 35 of the same; Fig. 3 a plan view of the inner form member of the cover in assembled position; Fig. 4 a side elevational view of the inner form member; Fig. 5 an end view of the inner form member; Fig. 6 a side elevational view of the upper member of the base form; Fig. 7 an end view of the same; Fig. 8 a side elevational view of the lower member of the base form and Fig. 9 an end view of the same.

45 Referring to the drawings the cover of the vault is made in the form or mold illustrated in Figs. 1 to 5, and the base in the form or mold illustrated in Figs. 6 to 9.

The inner member of the cover form comprises four sections 1, 2, 3 and 4, preferably 50 formed of metal. Each section consists of two vertical walls 5 and 6 with a top portion 7 integral with or connected to the vertical walls, the top portion being curved 55 transversely, and a flange 2 projecting laterally from the lower edge of the walls 5 and

6. Cleats 9 extend upwardly at suitable points along the outer edge of the flange and serve as guides for the exterior form member. The four sections are adapted to overlap when assembled—that is, section 1 overlaps sections 2 and 3, section 2 overlaps sections 3 and 4 and section 3 overlaps section 4. Apertures 10 are formed in the portions of the sections adapted to overlap and when 65 the sections are adjusted to the size of vault to be constructed screws 11 are inserted through registering apertures and engaged in brace 12 secured to uprights 13 secured to planks 14, the brace, uprights and planks 70 being of wood. The sections are placed on a wooden frame 15. The bracing structure within the form just described rigidly supports the form and prevents its collapse by the weight of the concrete when poured on 75 the form. The exposed apertures 10 not in use are suitably plugged to prevent the concrete from passing through the same.

The exterior form member comprises two side plates 16 of metal conforming to the 80 desired shape of the side walls of the cover, and two end plates or gates 17 also conforming to the desired shape of the ends of the cover. Preferably the top of the cover is convex and accordingly the upper edge 18 of 85 each gate is rounded to conform to the desired contour of the cover. The side plates at their lower edges abut the cleats 9 on the side portions of flanges 8 and in like manner the lower edges of gates 17 abut the 90 cleats 9 on the end portions of flanges 8. Rods 19 are inserted through apertures in the extremities of side plates 16 and wing nuts 20 are tightened on the rods to hold the plates in parallel relation, the outer faces of 95 the end gates abutting the said rods. Bracing bars 21 are secured to the side plates to make them rigid and thereby enable thin material for the plates to be used. The upper and lower edges of each side plate are arched 100 over as at 22 and 22' to stiffen the plate along said edges and bracing bars 23 are extended upwardly through apertures in the arched portions 22. A tie rod 24 with wing nut 25 is inserted through apertures in the 105 upper ends of said bars 23 to afford additional bracing of the side plates.

Each end gate is formed with a transverse outwardly flared portion 26 which form on the ends of the completed cover a transverse 110 shoulder or rib extending entirely across the end of the cover under which shoulders a

rope or chain is engaged for raising the cover first out of the mold and thereafter in handling the cover.

When the cover form is assembled as

- 5 above described the cement mixture is poured in between the inner and outer members of the form and as the upper edge of the side plates is reached the mixture applied is thicker in consistency so that it will
10 pile up above those sides and between the upper portions of the end plates and enable the operator to smooth off the top surface of the material by a bar or suitable tool, the upper edges of the end gates guiding the tool
15 to produce the desired convex top face to the cover.

The base form comprises two metallic sections 28 and 29. The bottom section 28 consists of a flat top portion 30 with outwardly and downwardly sloping sides 31 and a trough 32 extending around the lower edge of the side walls. The top section 29 consists of a four-sided shell open at its top and bottom which is placed over the bottom portion and rests on the outer wall 33 of the trough 32. The plastic material is poured onto the bottom section and tamped in between the walls of the shell and the side walls of the bottom section and smoothed off with a suitable tool guided by the upper edge of the shell. The trough 32 forms the flange about the base upon which the lower face of the cover seats when installed.

- 35 It is apparent from the foregoing that the mold is most simple in construction and readily set up and taken down. When a cover has been poured it is allowed to set in the mold and when fully set, the tie rods 40 are removed and the side plates and end gates are removed and the cover readily lifted off the inner form member. The exterior form is again assembled and another cover is poured with a minimum of labor.
45 The guide cleats 9 on the inner member of

the cover form center the exterior member of the cover form so that no adjustment of either member is necessary to properly center the same.

What we claim is:

1. A form for the uses and purposes described comprising an inner and an exterior member, the inner member being composed of four adjustably overlapping sections, a reinforcing frame within the inner member 50 to which the overlapping sections are removably secured, and guides on the inner member adapted to be engaged by the exterior member for centering the two members. 55

2. A form for the uses and purposes described comprising an inner and an exterior member, the inner member being composed of four adjustably overlapping sections, a reinforcing frame within the inner member 60 to which the overlapping sections are removably secured, the exterior member being composed of two side walls and two end walls and means on the inner member to center the exterior member with respect to the inner member. 70

3. A form for the uses and purposes described comprising an inner and an exterior member, the inner member being composed of a plurality of overlapping sections, means to reinforce and secure the said sections in 75 overlapped position, and the exterior member having separable end and side members and means to tie them together, each end member having its upper portion extended above the side members and its upper edge 80 conforming in outline to the desired contour for the top of the article to be made in the form, and each end member having an outwardly flared portion in its upper part and extending laterally of the same. 85

In witness whereof we have hereunto subscribed our names this 22nd day of March, 1921.

HAROLD H. DOSWELL.
ARTHUR E. KOVER.
